DESIGN FOR A HAIR DRIER OR THE LIKE

David Chapman, Chicago, Ill., assignor to Knapp-Monarch Company, St. Louis, Mo., a corporation of Missouri

Application December 14, 1937, Serial No. 73,592

Term of patent 7 years

To all whom it may concern:

Be it known that I, David Chapman, a citizen of the United States and a resident of Chicago, in the county of Cook and State of Illinois, have invented a new, original, and ornamental Design for a Hair Drier or the like, of which the following is a specification, reference being had to the accompanying drawing, forming part thereof.

Figure 1 is a perspective view of a hair drier or the like showing my new design.

Figure 2 is a top plan view thereof; and Figure 3 is a side elevational view thereof.

I claim:

The ornamental design for a hair drier or the like, substantially as shown.

DAVID CHAPMAN,
